UNITED STATES PATENT OFFICE.

CHARLES A. HUMPHREYS, OF CHICO, CALIFORNIA.

COUPLING-OPERATING MECHANISM.

1,203,199.

Specification of Letters Patent. Patented Oct. 31, 1916.

Application filed September 8, 1915. Serial No. 49,463.

To all whom it may concern:

Be it known that I, CHARLES A. HUMPHREYS, a citizen of the United States, residing at Chico, in the county of Butte and State of California, have invented certain new and useful Improvements in Coupling-Operating Mechanism, of which the following is a specification.

My invention relates to improvements in operating devices for car couplers, and more particularly to that class of couplers which have a swinging or radiating movement.

The objects of the invention are to provide coupler operating mechanism which will obviate an employee going between adjacent cars for the purpose of uncoupling the same; to provide mechanism of the character described which will permit uncoupling regardless of the angle at which the couplers may be disposed; and to provide a device which is extremely simple in construction and operation, and absolutely devoid of any parts which will tend to preclude freedom of movement.

To the accomplishment of the recited objects and others coördinate therewith, the preferred embodiment of my invention resides in the construction and arrangement hereinafter described, illustrated in the accompanying drawings and embraced within in the scope of the appended claims.

In said drawings—Figure 1 is a bottom plan view of a portion of a car equipped with my improved form of coupler operating mechanism. Fig. 2 is a detail perspective view of the coupler knuckle lock showing its connection with the coupler operating mechanism. Fig. 3 is a side elevation of the device, as shown in Fig. 1; Fig. 4 is a detail view of the draw-head, and Fig. 5 is a top plan view of the coupler partly broken away showing the manner of operating the knuckle.

In carrying out my invention, I support one end of a rock-shaft directly upon the bottom side of the "radial pocket" or pivotal point of the draw-bar, while the other end is connected to the coupler uncoupling knuckle lock. A crank depends vertically from the terminal of the shaft which is carried by the "radial pocket", and this in turn is connected to an operating lever which lies in a very accessible position near the outside of the car under-frame.

Referring more particularly to the drawings, the numeral 1 designates the under-

frame of a car, 2 the draw-head and 3 the draw-bar which is pivotally connected at its back end to a "radial pocket" 4. A bracket 5 is secured to the radial pocket 4 and projects a slight distance beyond the lower edge thereof where it is fashioned into a bearing 6 for the inner terminal of a rock-shaft 7. The opposite terminal of the rock shaft carries a slightly bent depending link 8 to which is pivotally connected at 9 an L-shaped rod 10. This rod passes beneath the draw-head and has its outer extremity curved so that it may be readily secured to an uncoupling lock eye or pull of the coupler 11, as at 12, the said eye being connected at its medial point to a link 13 pivotally secured to the knuckle lock 14, the knuckle being shown at 15. At opposite ends of eye 11 are fastened eye bolts 11' which extend transversely of the top and bottom of the coupler head and slide in ways 12'. A coiled spring 13' encircles each eye bolt and is maintained in its respective way 12' by a guide nut 14'. Upon again referring to the bracket, which may virtually be considered as a component part of the radial pocket, it will be seen that the bearing 6 has a medial opening 16 for the purpose of receiving and attaching to the rock-shaft one end of a vertical crank 17. The lower end of this crank is loosely secured to an eye 18 of a connecting rod 19 which is disposed at substantially right angles to the rock-shaft and is operated by the bell-crank lever 20 located on the longitudinal side sill 21 of the car.

In operation, when it is desired to uncouple the cars, the employee simply grasps the bell-crank lever 20, and pulls outwardly against the tension of spring 22, whereupon motion will be transmitted through the various parts previously described to open the knuckle 15 of the draw-head, as shown by dotted lines in Fig. 5.

The advantage accruing from the novel feature of connecting the rock-shaft and the connecting-rod directly to the pivotal point of the draw-bar is that the maximum latitude of movement of the draw-head and draw-bar is provided without in any way affecting the functioning of the coupler operating mechanism.

It should be understood that in broader aspects the invention comprehends not only the employment of the means described, but of equivalent means for performing the re-

cited functions. I reserve the right to effect such variations and modifications as may come fairly within the scope of the appended claims.

5 What I claim is:

1. In an operating device for car couplers, the combination of a draw head having a transversely movable unlocking device, a pivoted draw bar, a rock shaft extending substantially parallel with said draw bar and having its rear end substantially coincident with the pivot of the draw bar and having at its forward portion an off-set extremity, a rod extending beneath the draw head in a plane parallel with the plane of movement of the unlocking device and connecting the unlocking device with said extremity, and means connected to the rear end of said rock shaft for operating said shaft, whereby the rod is moved in the direction of its length to effect a movement of said unlocking device.

2. In an operating device for car couplers, the combination of a draw head having a transversely movable unlocking device, a

pivoted draw bar, a rock shaft, extending substantially parallel with said draw bar and having its rear end substantially coincident with the pivot of the draw bar and having at its forward portion an off-set extremity, a substantially L-shaped rod having its longer portion extending beneath the draw head in a plane parallel with the plane of movement of the unlocking device and terminally connected to said extremity, while its shorter portion is disposed upwardly to one side of the draw head and has its end connected to said unlocking device, and means connected to the rear end of said rock shaft for operating said shaft, whereby the rod is moved in the direction of its length to effect a movement of said unlocking device.

30 In testimony whereof I affix my signature in the presence of two witnesses.

CHARLES A. HUMPHREYS.
